(57) **CLAIM**

The ornamental design for a phone holding device, as shown and described.

DESCRIPTION

FIG. 1 is a top, right, front perspective view of a phone holding device showing my new design;

FIG. 2 is a top, right, back perspective view thereof;

FIG. 3 is a top plan view thereof;

FIG. 4 is a bottom plan view thereof;

FIG. 5 is a front elevation view thereof;

FIG. 6 is a back elevation view thereof;

FIG. 7 is a cross-sectional view thereof, taken along line 7-7 in FIG. 3;

FIG. 8 is a right side elevation view thereof;

FIG. 9 is a cross-sectional view thereof, taken along line 9-9 in FIG. 3;

FIG. 10 is a right side elevation view thereof, shown in an alternate position;

FIG. 11 is a top, right, front perspective view thereof; and, FIG. 12 is a top, left, back perspective view thereof shown in an environment of use.

Broken lines illustrate portions of the phone holding device that form no part of the claimed design. Additional broken lines in FIG. 12 illustrate environment and form no part of the claimed design.

1 Claim, 8 Drawing Sheets
